UNITED STATES PATENT OFFICE

GEORGE E. THACKRAY, OF BETHLEHEM, PENNSYLVANIA

SHEET PILING

Application filed May 21, 1929. Serial No. 364,904.

Heretofore various forms of sheet piling which have been used have an interlocking or tongue and groove style of longitudinal joint between the piling sections which joint is located at or near the center of the piling wall. This form of construction applies especially to those styles which are known as deep arch, channel or trough shape piling the sections of which are preferably of steel, formed in a rolling mill.

Piling arranged in this manner is not adapted to develop in use its full flexural strength to resist the forces or loads to which it is subjected, comprising the pressures of earth, water, mud, sand, loose rock or mixtures of such or other materials.

Joining the piling by merely transversely interlocking the sections thereof at or near the center of the piling wall, causes such an arrangement to be structurally weak for the reason, that in flexure, the longitudinal shear is the maximum along the practically loose interlock at or adjacent to the center line of the combined sections or near what is known as the neutral axis of the combined sections, and thus causes the different and opposing sections to slide past each other under the conditions of use and in such a way that the combined strength of the sections is not developed. Such a wall has a flexural strength only equal to that of a series of single sections not interlocked or joined. In order to obviate this difficulty I provide piling, of sections which can be produced by rolling in a rolling mill, and before driving or putting them into position I secure two or more of said sections together along what will become the intermediate portion of the piling wall.

Such joined sections form a piling wall which when subject to flexure, will develop their full or combined strength and such construction may be about twice as strong in flexure as a combination of the sections considered separately as they must be when merely loosely interlocked, as previously described.

In calculating the strength of such sections by engineering mathematics the section modulus is used, which is a function of the area of

the cross section of a member in flexure, ordinarily calculated about the neutral axis of the section passing through its center of gravity. The flexural strength of a member is directly proportional to its section modulus, which is a function generally expressed in inches to the third power.

This section modulus is determined from what is known as the moment of inertia of the cross section which is the sum of the products of all the infinitesimal or elementary areas of the cross section by multiplying these areas by the squares of their respective distances from the neutral axis.

This expression of the moment of inertia is generally stated in inches to the fourth power. The section modulus is derived from the moment of inertia by dividing it by the normal distance in inches from the neutral axis to that portion of the section most remote from that axis, producing then an expression of function which is, as before stated, in inches to the cube or third power.

Each of the piling sections is substantially as large or deep as certain rolling mills can produce and these, as heretofore assembled in a piling wall do not develop the flexural strength which could be had by their combination.

By securing these together by welding or otherwise, I produce a combined section which is larger and deeper than such rolling mills can produce but substantially integral and of much greater strength than the prior piling walls which is only that of the separate members.

One of the forms of sheet piling which I use may be of channel or trough shape with hooked or interlocking portions of various shapes at the ends of its legs adapted to be locked thereby to the adjacent section by sliding lengthwise thereof.

Such a joint however by reason of the construction, method of assembling or so-called interlocking, has substantially no structural strength, to resist the longitudinal shear, and in order to provide this I weld or otherwise join two or more sections together at or near their interlocking portions. The

ends of the joined legs may also be plain, provided with hook joints or otherwise.

The welds may be comparatively short, but preferably arranged and distributed at such distances apart as to best withstand the longitudinal shear at their respective locations.

In other words I may make more welds at the locations where the longitudinal shear is greatest and arrange them substantially in number or proportion to the longitudinal shear stress.

I may either make the welds of the same length and space them at different distances as indicated, or space them substantially equally and make them larger where the longitudinal stress is greater.

The longitudinal shear is the stress lengthwise of the legs or of their junction, which has a tendency to cause one section to move longitudinally of the adjacent section and, when this is not resisted by firmly securing the sections together, the flexural strength of the combination is not developed. This invention, however, is such that, by securing the two adjacent sections together by welding or otherwise, the full strength of the combination is had and is several times greater than that of the two sections not so joined.

The method of calculating the longitudinal shear by engineering mathematics is based upon the cross section and arrangement of the piling and a knowledge of the pressures to be resisted, the locations and characters of the supports of the piling sections including the resistance of the earth or other material at their lower ends, and the supports given by tie rods or other bracing near the top or elsewhere.

The resistance of the piling to flexure is proportional to the sectional modulus, and the longitudinal shear at various locations throughout the length of the piling when acting as a unit, is determined from a knowledge of the perpendicular shear or that at right angles to and at various points along the longitudinal axis of the piling, produced by the various forms of loading and supports.

The longitudinal shear at any location is the product of the aforesaid perpendicular shear by the statical moment of the area of the section included between the longitudinal surface of shear at that point and the extremity of the section on the same side of the longitudinal axis, divided by the moment of inertia of the section around its neutral axis through that point.

I may use other means of securing the sections together including riveting, if the sections lend themselves to such joinder, but in other cases may use welding or other means, whereby two or more sections may be joined together before driving in position, or in

some cases where the walls are accessible, the joining may be done after the sections are in place.

Under certain circumstances the piling sections could even be welded under water, if necessary, but generally such construction would be avoided on account of the unnecessary amount of trouble and expense.

By securing the sections together in the manner indicated I provide a wall the section modulus of which is about twice as great as that of the sections when not so secured.

Having thus given a general description of my invention I will now, in order to make the matter more clear, refer to the annexed sheets of drawings which forms part of this specification and in which like characters refer to like parts:

Fig. 1 is a vertical cross sectional elevation through a bulkhead provided with my piling.

Fig. 2 is an elevation of the same looking from the outer or water side.

Fig. 3 is a cross section on a larger scale of one form of my piling, showing the sections in interlocked position.

Fig. 4 is a front elevation of two sections of piling showing the approximate locations of the welds or other fastenings for securing the two sections together.

Fig. 5 is a cross section, on a larger scale, of one form of interlocking joint, provided with welds for securing two sections together.

Fig. 6 is a cross section on a larger scale of the interlocking ends of two sections secured together by welding to filler bars and to the sections.

Figs. 7 and 8 are cross sections of other forms of my sheet piling showing two sections secured together.

Fig. 9 is a cross section of a ball and socket type of joint, some of which may be welded or secured together and others not so secured.

Fig. 10 is a cross section of a hook type of joint, some of which may be welded or secured.

The styles of joints shown in Figs. 7, 8, 9 and 10 have the joint portions made as small as possible to conserve material, as little steel is needed at or near the neutral axis, but it must be secured together in order to produce proper resistance to shear.

Fig. 11 is a cross section showing the plain legs of two sections secured together by rivets.

Referring now to the characters of reference on the drawings:

A section of piling in general is indicated by 1, and is provided with legs 2 and flange 3, while the ends of the legs are formed to provide the interlocking portions 4 and 5. As shown in the modified forms of Figs. 7 and 11, the end portions 6 of the legs are straight and overlapping as shown, while in Fig. 8 the interlocking or hooked portions 7 are somewhat smaller and lighter for the sake of economy.

Preferably two of these piling sections are secured together by the welds 8 or otherwise as desired, or more than two can be secured together in cases where a greater number can be handled, driven and put into final position.

As illustrated in Fig. 6 filler pieces or bars 9 may be introduced with a weld 8 on either side to facilitate the joinder.

As illustrated in Fig. 4 the welds or joinings of two sections are indicated at 8 and at other locations similarly marked by dark lines and these are shown as of approximately the same length but spaced at distances apart corresponding to the extent of the longitudinal shear of the piling in flexure, due to the pressure of the earth or other material which it holds in position.

This arrangement of joining will be different for different cases for the reason that the positions and amounts of the longitudinal shear will vary with changed proportions and dimensions of the structure, the pressure of the fill and loading, the relative locations, character and resistance of the earth or other support for the lower ends of the piling, and the number and positions of the anchors or other bracing for the other and upper portions of the piling.

The arrangement of welds or joinings therefore is merely suggestive and subject to such modification as may be desirable.

The welds as shown are arranged to properly resist the longitudinal shear and where the shear is less they are arranged at greater distances apart for the purpose of economy, but where needed they are closer together.

It should also be noted that longer welds are shown at the top and bottom of the piling to more securely join the ends together to better resist the stresses of driving.

The welds or joinings can also be arranged at substantially equal distances apart, but of different lengths or strengths sufficient to properly resist the shear stresses.

The earth or other bottom of a harbor is indicated at 10, the water surface is 11, while 12 and 13 indicate timber fenders secured to the upper part of the piling wall; 14 is a waling strip composed of two channels extending longitudinally of the piling wall and 15 is one of a series of tie rods which, in connection with the waling strip, holds the upper portion of the wall, the inner ends of the tie rods being secured to a braced system composed of the approximately vertical piles 16, the batter piles 17 and the horizontal timbers 18 and 19 as illustrated.

The fill of earth or other material retained by the wall is indicated as 20 and the pavement on top of the bulkhead is indicated as 21.

The approximate location of the maximum bending moment and the zero or minimum shear is indicated at 22.

Referring to Fig. 9, one or more piling sec-

tions may be welded or secured together at the location indicated as 23 and referring to Fig. 10 one or more piling sections may be welded or secured together at the location indicated as 24.

As shown in Fig. 11 the end portions 6 of the plain legs are secured together by a row of rivets indicated as 25.

The number of sections which may be secured together will depend upon the ability to handle and place them in position, that is:—to interlock one of the outer ones with an outer section of the piling.

In general however the piling wall will have its full flexural strength to resist shear if only two of the piling sections are secured together.

In order to produce a piling wall of the greatest efficiency and maximum of strength with a minimum amount or weight of piling metal I prefer to make the leg portions of each piling section as thin and the flange portions as thick as practicable dependent upon the possibilities of producing the same in a rolling mill and straightening or finishing them after rolling, and also with due regard to the relative proportions of these parts to perform the duty required.

I also prefer to make the interlocking hooks, if such are provided, small and light in weight with only sufficient strength to serve their purpose, that is, to hold the piling sections in proper relation. The hook portions of my piling sections need not be as strong as those of the prior forms for the reason that my unitary construction, provided by rigidly securing two or more sections together, will obviate the necessity of the heavier and stronger types of hooks or interlocking members.

Such a construction provides the greatest practicable amount of metal the farthest removed from the neutral axis of the piling wall and also uses the least amount of hook and leg metal at or near the said axis, all of which conduces to economy of material by furnishing the maximum of strength and section modulus per pound of metal.

Where great strength is necessary I prefer to make the separate sections of deep trough form as the strength in flexure is proportional to the square of the depth.

But where flexibility is desired, in order that the sections will, due to pressure of use, be forced together to close the interlocking joints and thus make the walls more watertight, I then make them of less depth for this reason.

Each portion of piling will consist of a plurality of sections rigidly united by their inner legs, and more loosely connected to the adjacent portions by the interlocking of their outer legs.

Having thus described my invention what

I claim and desire to secure by Letters Patent is:

1. Sheet piling composed of at least two trough sections having their edges joined together by two part interlocking portions formed thereon, and welds arranged at varied intervals along the interlocking portions, in proportion to the stresses produced by the longitudinal shear due to the tendency to flexure thereof. 5
2. Sheet piling composed of two or more sections of trough form, each provided with two part interlocking hook portions, adapted to hold them together transversely, and welds arranged along the interlocking portions in proportion to the longitudinal shear due to the tendency to flexure, said welds being adapted to resist relative longitudinal movement of the joined sections. 15
3. A plurality of sheet piling sections of trough form, each having a flange and two legs projecting therefrom, said legs each having two part hook portions at their ends mutually interlocked, said sections being further secured together by welding their interlocking hooks, said welds being of strength in proportion to the longitudinal shearing stresses due to the tendency to flexure. 25
4. Sheet piling composed of a plurality of trough-shaped sections, each provided with integral two part hook ends, adapted to join adjacent sections to resist transverse stresses, groups comprising two or more adjacent sections secured firmly together by welds which are of strengths proportional to the longitudinal shearing stresses due to the tendency to flexure. 35
5. Sheet piling composed of a plurality of trough-shaped sections provided with integral two part hook edges adapted to be interlocked, arranged in groups comprising two or more adjacent sections further secured firmly together at their hook edges, said latter securing being in substantial proportion to the longitudinal shearing stresses due to flexure and stronger at the ends to resist the stresses of driving and the resistance thereto. 45
6. Sheet piling composed of a plurality of sections of trough form, each having a flange and two thinner legs projecting therefrom, two part hook ends on said legs adapted to interlock and hold the sections transversely, two or more adjacent sections being secured firmly together by means whose resistance is proportional to the longitudinal shear due to flexure. 55
7. Sheet piling composed of a plurality of sections of trough form, each having a flange and two thinner legs projecting therefrom, two part hook ends on said legs adapted to interlock and hold the sections transversely, two or more adjacent sections being secured firmly together by means whose resistance is proportional to the longitudinal shear due to flexure, the end portions being more strongly secured together longitudinally to further resist the driving and resistance stresses. 65
8. Sheet piling, comprising a plurality of trough sections, each having a two part hook on one edge and a one part hook on the other edge adapted to interlock with the adjacent sections on each side thereof, the one part hooks being further and firmly secured together by means adapted to resist longitudinal shear due to flexure. 70
9. Sheet piling composed of a plurality of trough sections each of which has a two part hook on one edge and a plain unhooked other edge, a pair of which are interlocked by their hooked edges, the other plain edges being adjacent and secured firmly together at intervals by means proportional to the longitudinal shear at their respective locations. 75
